Primary Examiner — Mary Ann Calabrese*Assistant Examiner* — Mark David Wolfley(74) Attorney, Agent, or Firm — George D. Raynal(57) CLAIM

The ornamental design for a frame for infant exerciser as shown and described.

DESCRIPTION

FIG. 1 is a perspective view of a frame for infant exerciser showing my new design;

FIG. 2 is a front view thereof, the rear view being a mirror image;

FIG. 3 is a left side view thereof, the right side view being a mirror image;

FIG. 4 is a top view thereof;

FIG. 5 is a bottom view thereof; and,

FIG. 6 is an enlarged view of the portion encircled in FIG. 1.

The broken lines illustrate portions of the frame for infant exerciser which form no part of the claimed design.

1 Claim, 5 Drawing Sheets(56)
